CLAIM

We claim the ornamental design for an early entry concrete saw, as shown and described.

DESCRIPTION

FIG. 1 is a front perspective view of an early entry concrete saw in accordance with an embodiment of the present invention.

FIG. 2 is a front view of the early entry concrete saw of FIG. 1.

FIG. 3 is a rear view of the early entry concrete saw of FIG. 1.

FIG. 4 is a right side view of the early entry concrete saw of FIG. 1.

FIG. 5 is a left side view of the early entry concrete saw of FIG. 1.

FIG. 6 is a top view of the early entry concrete saw of FIG. 1; and,

FIG. 7 is a bottom view of the early entry concrete saw of FIG. 1.

The portions of the early entry concrete saw shown in broken lines are included for the purpose of illustrating environment and form no part of the claimed design.
